UNITED STATES PATENT OFFICE.

JOSEPH C. LANDES, OF COLLEGEVILLE, PENNSYLVANIA.

AUTOMATIC GAS-LIGHTER.

968,486.

Specification of Letters Patent. Patented Aug. 23, 1910.

Application filed February 23, 1907. Serial No. 358,765.

To all whom it may concern:

Be it known that I, JOSEPH C. LANDES, a citizen of the United States, residing at Collegeville, county of Montgomery, State of Pennsylvania, have invented a new and useful Automatic Gas-Lighter, of which the following is a specification.

My invention consists of an improvement in automatic gas lighters similar to the form shown in my Letters Patent No. 870,891, patented November 12th, 1907, the object being not only to seal the movable members within the top of the casing so as to prevent leakage of gas therein but also to automatically light the burner by the movement of the movable parts and to automatically extinguish the same.

Figure 1 represents a side elevation of a lighter embodying my invention. Fig. 2 represents a central vertical section thereof. Fig. 3 represents, in elevation, the device for actuating the valve controlling the burner. Fig. 4 represents a sectional view of a portion of the igniter.

Similar numerals of reference indicate corresponding parts in the figures.

Referring to the drawings. A designates the exterior casing of the device, the same being open at the top and practically closed at the bottom.

B designates the interior casing which is suitably supported by the base C of the casing A and is open at the top and closed at the bottom excepting for the ports hereinafter designated.

D designates a rising and falling vessel or float which is closed at the top and open at the bottom, the sides of the said vessel being interposed in the space or chamber E between the side walls of the casings A and B. In said space is placed a quantity of mercury as F, into which the vessel D dips and forms a seal for the bottom of the latter.

Connected with a suitable portion of the base C is a pipe G which supplies gas to the burner H.

Suitably fitted upon the pipe G is a rising and falling pipe J, which is suitably connected with the vessel G and to which pipe is secured the plate K, the latter carrying an arm L having a movable connection with the link M which is also movably connected with the lever N, said lever being suitably mounted and having a spring actuated dog E' suitably connected and adapted to engage upon upward movement, with a tooth

of the ratchet F', which is connected with the stem G' of the valve on the interior of the casing P, said valve controlling the flow of gas through the pipe G, it being understood that the valve is so arranged that upon upward movement of the pawl E' and proper rotation of the stem G', it will permit the flow of gas through the pipe G to the burner and upon the next upward movement of the pawl E', it will actuate the valve to close the flow of gas to the burner.

Q designates an insulated block suitably supported on the casing A from which extends the rod R carrying one member of the contact device. Suitably connected with the plate K is the standard S which carries the other member T of the contact device and which is normally out of contact with the member carried by the rod R, which latter is situated in the path of movement of the contact member T.

Carried by the standard S and insulated therefrom is the cage or shell H' which is in suitable connection with the contact piece T and on the interior of which is a stem J', which is in suitable connection with the cage H', a filament or wire K' being suitably connected with said stem J' and also with a second stem L' which is insulated from the cage H' but is in contact with the standard S.

U designates a battery having a conductor V in suitable connection with the rod R and a suitable conductor W in connection with the standard S.

Rising from the base C and surrounding the pipes G and J is a pipe X which is closed at the bottom and open at the top. In the space or chamber Y between the pipes G, J and X is a quantity of mercury Z in which the lower end of said movable pipe J dips as a seal for the bottom thereof.

In the base C are the ports A' and B'—B', the same being in communication with the supply nipple C', the port A' opening to the pipe G and the port B'—B' opening into the inner casing B.

The operation is as follows:—It will be understood that the automatic gas controller is in suitable communication with the main gas supply and can be situated at any desired point. In order to light the burner, the gas pressure from the main is increased and the gas passing through the nipple C' enters the pipe G and passes through the ports B' entering the interior casing B and

raises the vessel or float D. This carries with it the pipe J and elevates the plate K and in so doing, it carries with it the arm L, the link M and raises the lever N carrying 5 with it the pawl E', which engaging with one of the teeth of the ratchet F', rotates the same turning the stem G' so that the valve is in suitable position for permitting the gas to flow through the pipe G, to the 10 burner H, at the same time the standard S is elevated causing the contact piece T to contact with the piece carried on the rod R. This closes the circuit in which the battery U is situated and the wire or filament K' 15 will glow, so that the gas will be ignited at the burner H, it being understood that the contact pieces will remain in contact while the pressure of the gas holds the same in position.

20 As soon as the burner is ignited, the pressure is suitably decreased and the float D and the parts carried thereby are lowered, but the pawl E' in lowering rides freely over the teeth of the ratchet F' without actuating the valve so that the gas continues 25 to flow through the pipe G.

When it is desired to extinguish the gas, the pressure is again increased, raising the float D with the parts which it carries and 30 causing the pawl E' to again rotate the ratchet F' and stem G carrying with it the valve controlling the supply of gas to the burner, which is thus closed, so that the light is extinguished and the pressure is decreased, the parts assuming their normal 35 positions.

As the lower end of the vessel is situated in the mercury in the chamber E, the resultant seal prevents the gas that enters the casing B from escaping or leaking into the interior casing A and the seal resulting from the movable pipe dipping into the mercury Y prevents the gas that enters the casing D from escaping or leaking into the pipe J.

45 D' designates a pipe for filling the chambers E and Y with mercury, the same being in communication with the said chambers, so that by pouring mercury in said pipe it will be properly located in said chambers.

50 Having thus described my invention, what I claim as new and desire to secure by Letters Patent, is:—

1. In a device of the character described, a casing, a stationary contact piece supported thereby, a float, a movable contact piece carried by said float, a valve for controlling the supply of gas to the burner, means in suitable connection with said valve and said float whereby said valve is actuated by the 55 movement of said float, and a filament movable with the movable contact and brought thereby to a point adjacent the burner said contact pieces being held in contact while said float is elevated, whereby the circuit 60 will be closed until the float is lowered.

2. In a device of the character described, a casing, a contact piece carried thereby, a float, a movable contact piece carried by said float, a valve controlling the supply of gas to the burner, means connected with said valve and with said float for opening said valve upon one upward movement of the float and for closing said valve in the next upward movement of said float, and a filament movable with the movable contact and brought thereby to a point adjacent the burner said contact pieces being held in contact while said float is elevated, whereby the circuit will be closed until the float is lowered.

3. In a device of the character described, a casing, a stationary contact piece carried thereby, a float, a movable contact piece carried by said float, a battery in suitable connection with said movable and said stationary contact pieces, a filament in the circuit movable with the movable contact and adapted to be located adjacent the burner when the float is elevated, and a valve suitably actuated by the movement of said float to control the supply of gas to the burner.

4. In a device of the character described, a casing, a stationary contact piece carried thereby, a float, a movable contact piece carried by the said float and adapted to contact 95 with the first mentioned piece when the float is elevated, a valve, a spring-actuated dog adapted to engage with said valve to rotate the same upon the upward movement of said float and to freely pass the same upon the 100 downward movement of said float, a filament movable with the movable contact to be brought adjacent the burner by the raising of the float and an electric circuit closed by said contact pieces and adapted to ignite 105 the gas at the burner, said contact pieces being held in contact while said float is elevated, whereby the circuit will be closed until the float is lowered.

5. In a device of the character described, a casing, a stationary contact piece carried thereby, a float, a movable contact piece carried thereby, a filament movable with the movable contact to be brought adjacent the burner by the raising of the float said contact pieces being held in contact while said float is elevated, whereby the circuit will be closed until the float is lowered, a valve controlling the supply of gas to the burner, a ratchet carried by said valve, and a spring 110 actuated dog operated by the movement of said float and adapted to rotate the valve upon the upward movement of said float and to freely pass the ratchet upon the downward movement of said float.

6. In a device of the character described, a casing, a stationary contact piece supported thereby, a float, a guiding member for said float with a seal for the same, a movable contact carried by said guiding mem- 125 130

- ber, a filament movable with the movable contact to be brought adjacent the burner by the raising of the float, a valve for controlling the supply of gas to the burner, 5 pivotal means connected with said guiding member, and connections between said pivotal means and the valve stem for alternately opening and closing said valve by successive upward movements of the float.
- 10 7. In a device of the character described, a casing, a stationary contact piece supported thereby, a float, a guiding member for said float with a seal for the same, a movable contact carried by said guiding member, a valve for controlling the supply of gas to the burner, pivotal means connected with said guiding member, connections between said pivotal means and the valve stem for alternately opening and closing 15 said valve by successive upward movements of the float, a cage movable with the movable contact, and a filament in said cage and movable by the raising of the float to a point adjacent the burner.
- 20 8. In a device of the character described, a casing, a burner mounted on said casing,
- 25 a contact adjacent said burner, a float in said casing, a contact carried by said float, a gas supply valve for said burner, actuating connections between said valve and said float, a filament in circuit with said float contact and located in close proximity to said burner, and means to raise said float to bring said contacts together and actuate said valve connections to open said valve. 30
- 35 9. In a device of the character described, a casing, a burner mounted on said casing, a contact adjacent said burner, a float in said casing, a contact carried by said float, a gas supply valve for said burner, actuating connections between said valve and said float, a filament in circuit with said float contact and located in close proximity to said burner, a cage inclosing said filament, and means to raise said float to bring said contacts together and actuate said valve connections to open said valve. 40
